UNITED STATES PATENT OFFICE

161,641

POCKET HAT BRUSH

Elzie F. Newman, Logansport, Ind.

Application April 28, 1949, Serial No. 2,313

Term of patent 7 years

(Cl. D9—2)

To all whom it may concern:

Be it known that I, Elzie F. Newman, a citizen of the United States, residing at Logansport, in the county of Cass and State of Indiana, have invented a new, original, and ornamental Design for a Pocket Hat Brush, of which the following is a specification, reference being had to the accompanying drawing, forming part thereof.

I claim:

The ornamental design for a pocket hat brush, as shown.

ELZIE F. NEWMAN.
